UNITED STATES PATENT OFFICE

FELIX R. RAPIDS, OF CHICAGO, ILLINOIS

HAIR CLEANING DEVICE

Application filed July 29, 1929. Serial No. 381,775.

My invention relates to improvements in hair cleaning devices, and it consists in the combinations, constructions, and arrangements herein described and claimed.

5 An object of my invention is to provide a hair cleaning device in which the teeth are formed in such a manner that a maximum amount of dandruff is loosened from the scalp, and in which openings are provided 10 in the teeth and arranged in such a manner with respect to the points of the teeth that a maximum amount of the dandruff is drawn into the openings.

15 A further object is to provide a hair cleaning device in which the teeth are arranged to separate the hair in such a manner that the strands are thoroughly cleaned by reason of the movement of the air passing through the openings in the teeth, and in which the 20 teeth are further adapted to loosen dandruff, etc. adhering to the hair throughout its entire length and depth.

25 A further object is to provide a hair cleaning device which, while primarily designed for the purpose of removing dandruff, dust, etc., is equally well adapted to remove any loose hair.

30 A further object is to provide a hair cleaning device which serves a secondary purpose in that it may be employed as a blower for drying the hair, scalp, etc.

35 A further object is to provide a device of the type described in which sharp corners and the like have been reduced to a minimum thereby providing a device which may be easily cleaned.

40 Other objects and advantages will appear in the following specification, and the novel features of the invention will be particularly pointed out in the appended claims.

45 My invention is illustrated in the accompanying drawings, forming part of this application, in which

Figure 1 is a sectional view taken along the line 1—1 of Figure 2,

Figure 1A is a sectional view taken along the line 1A—1A of Figure 2,

Figure 2 is a front elevation of my invention,

50 Figure 3 is a rear elevation of a portion of

the device shown in Figure 2 and illustrating the device used in connection with a removable cap or cover,

Figure 4 is an end elevation of the device shown in Figure 3,

55 Figure 5 is an enlarged sectional detail view showing the manner in which the cap or cover is removably attached to the device,

Figure 6 is an end elevation of a slightly modified form of my invention, and

60 Figure 7 is a further modification of my device.

In carrying out my invention I make use of a hollow body portion 1 provided with an integral shank portion 2. The shank 2 is 65 also hollow and is preferably connected with a flexible tube 3 which is operatively connected with a vacuum device, not shown. The body portion 1 is provided with a plurality of teeth 4 having one of their edges provided with openings 5 throughout their entire length. The teeth are provided with side walls 6 and edges 7 disposed angularly with respect to the edges provided with the openings.

70 The ends of the teeth may be formed as at 8, see Figure 2, and slightly rounded as at 9 in Figure 1. The opening 5 communicate with the opening in the body portion 1 which is in communication with the openings 80 in the shank 2 and the tube 3. The walls of the teeth 4 are preferably arranged in parallel relation.

75 In operation the teeth of the hair cleaning device are moved through the hair in substantially the same manner as the ordinary comb is used when combing the hair. The points of the teeth tend to loosen any dandruff adhering to the scalp and the movement of the air through the device, which 85 must of necessity pass through the openings in the teeth, draws the loosened dandruff, dust, and loose hair through the teeth, the body portion, and finally to the receptacle associated with the vacuum mechanism. The 90 teeth of the device may be moved through the hair in either direction with respect to the open edges of the teeth.

95 In referring to Figure 1 it will be noted that the openings in the teeth provide a min-

imum amount of restriction as when long hair and the like is passing through the openings.

The teeth, in being arranged in parallel relation and in proper spaced relation, tend to separate the hair in thin strands which are thoroughly cleaned by reason of the movement of air through the openings 5. Any dandruff and the like which is adhering to the hair will be loosened by the edges of the teeth. It will also be seen that when the points of the teeth are moved over the scalp the dandruff loosened by the teeth is so positioned with respect to the openings 5 that the dandruff will be immediately drawn into the openings.

In Figure 2 I have shown the points of the teeth as being arranged in a slightly curved formation. This formation permits the ends of the teeth to substantially conform to the curvature of the scalp. In Figures 3 and 4 I have shown a cap or cover 10 which may be mounted adjacent the edges 7 of the teeth. The cover prevents the movement of air between the teeth. The cover may be advantageously employed when using the device in cleaning relatively short hair. When the cover is placed in position and the open edges of the teeth presented to the scalp, the moving air must of necessity pass relatively close to the scalp. The cover may be made of relatively thin material which permits a certain amount of flexing of the end portions 11. Each end 11 may be provided with a recess 12 for receiving lugs 13 associated with a pair of the teeth 4. The construction is such that the cover may be slipped into position and the lugs 13 will firmly hold the cover in position while the device is being used.

In Figure 6 I have shown a slightly modified form of my construction in which the edges 4' and 7' are tapered toward each other with respect to the parallel sides 14 and 15. In Figure 7 the teeth are rounded as at 16. The operation of each form is, of course, substantially identical. In either form the cross sectional area of the opening in the shank 2 and the body portion 1 should preferably be equal to or greater than the total cross sectional area of the openings in the teeth.

I claim:

1. A pneumatic hair cleaning device comprising a hollow body portion having a plurality of substantially triangular hollow teeth communicating with the interior of the body portion, said teeth being flat and provided with openings on one side of said teeth extending substantially the entire length of said side of the teeth, each of said teeth having flat side walls, all of the side walls of all of said teeth being substantially parallel and spaced-apart from each other, said sides of all of said teeth provided with said openings

being positioned substantially in a single plane, said openings being adapted to be moved adjacent the scalp.

2. A pneumatic hair cleaning device comprising a hollow body portion, and a plurality of triangular hollow teeth connected with the body portion and communicating with the interior of the latter, each of said teeth being tapered in the direction of their outer ends and provided with openings on one side extending substantially the entire length of said side of the teeth, said teeth being spaced-apart and parallel to each other, said sides of all of said teeth being positioned substantially in a single plane, said openings being adapted to be moved adjacent the scalp.

3. A pneumatic hair cleaning device comprising a hollow body portion, and a plurality of substantially triangular hollow teeth connected with the body portion and communicating with the interior of the same, said teeth being flat and wider at their bases than at their opposite ends and provided with openings in one side of said triangular teeth extending substantially from their bases to their outer ends, said teeth being substantially parallel to each other, all of said sides having said openings being positioned substantially in a single plane, said openings being so arranged in said teeth that said openings may be moved adjacent the scalp in a manner whereby said device may remove the dandruff directly from the scalp.

4. A pneumatic hair cleaning device comprising a hollow portion, and a plurality of flat hollow teeth, said teeth being provided with longitudinal openings, said openings being positioned substantially in a single plane, each of said teeth being positioned opposite one another and having side wall portions, said side wall portions being spaced-apart, opposite and substantially parallel to each other, each of said openings being so positioned on said teeth that said openings may be placed substantially opposite and adjacent the scalp in a manner whereby the dandruff on the scalp may be drawn into said hair cleaning device.

5. A pneumatic hair cleaning device comprising a hollow body portion having a plurality of substantially triangular hollow teeth communicating with the interior of the body portion, said teeth being flat and provided with openings on one side of said teeth extending substantially the entire length of said side of the teeth, each of said teeth having flat side walls, all of the side walls of all of said teeth being substantially parallel and spaced-apart from each other, said sides of all of said teeth provided with said openings being positioned in a slightly curved formation, said openings being adapted to be moved adjacent the scalp.

6. A pneumatic hair cleaning device comprising a hollow body portion and a plurality

of triangular hollow teeth connected with the body portion and communicating with the interior of the latter, each of said teeth being tapered in the direction of their outer ends
5 and provided with openings on one side extending substantially the entire length of said side of the teeth, said teeth being spaced-apart and parallel to each other, said sides of all of said teeth being positioned in a
10 slightly curved formation, said openings being adapted to be moved adjacent the scalp.

7. A pneumatic hair cleaning device comprising a hollow body portion and a plurality of substantially triangular hollow teeth
15 connected with the body portion and communicating with the interior of the same, said teeth being flat and wider at their bases than at their opposite ends and provided with openings in one side of said triangular teeth
20 extending substantially from their bases to their outer ends, said teeth being substantially parallel to each other, all of said sides having said openings being positioned in a slightly curved formation, said openings being
25 so arranged in said teeth that said openings may be moved adjacent the scalp in a manner whereby said device may remove the dandruff directly from the scalp.

8. A pneumatic hair cleaning device comprising a hollow portion and a plurality of flat hollow teeth, said teeth being provided with longitudinal openings, said openings being positioned in a slightly curved formation, each of said teeth being positioned opposite one another and having side wall portions, said side wall portions being spaced-apart, opposite and substantially parallel to each other, each of said openings being so positioned on said teeth that said openings
35
40 may be placed in a manner whereby the dandruff on the scalp may be drawn into said hair cleaning device.

Signed at Chicago, in the county of Cook, and State of Illinois, this 24th day of July,

45 A. D. 1929.
